Primary Examiner — Sandra S Snapp*Assistant Examiner* — Holly E Thurman(74) *Attorney, Agent, or Firm* — Walter Ottesen, P.A.(57) **CLAIM**

The ornamental design for a mount for a surgical microscope, as shown and described.

DESCRIPTION

FIG. 1 is a left side elevation view of a mount for a surgical microscope of our new design;

FIG. 2 is a right side elevation view of the mount for the surgical microscope of FIG. 1;

FIG. 3 is a top plan view of the mount for the surgical microscope of FIG. 1;

FIG. 4 is a bottom plan view of the mount for the surgical microscope of FIG. 1;

FIG. 5 is a rear elevation view of the mount for the surgical microscope of FIG. 1;

FIG. 6 is a front elevation view of the mount for the surgical microscope of FIG. 1; and,

FIG. 7 is a perspective view of the mount for the surgical microscope of FIG. 1.

The broken lines depict portions of a mount for a surgical microscope that form no part of the claimed design.

1 Claim, 6 Drawing Sheets(56)
